CLASP

Lee Oliver, Milford, Conn., assignor to The Connecticut Web and Buckle Company, Bridgeport, Conn., a corporation of Connecticut

Application November 29, 1943, Serial No. 512,125

5 Claims. (Cl. 24—250)

This invention relates to clasps for garments, particularly a clasp for use on men's suspenders and similar garment supports, and has for an object to provide an improved and simplified clasp which will effectively grip the garment and does not require the use of springs outside of the resiliency of the parts themselves.

It is also an object to provide a clasp of the type in which there is a stationary and a movable jaw and an operating lever for shifting the movable jaw to clamping position, with improved means for mounting the movable jaw.

With the foregoing and other objects in view I have devised the construction illustrated in the accompanying drawing forming a part of this specification. It is, however, to be understood the invention is not limited to the specific details of construction and arrangement shown but may embody various changes and modifications within the scope of the invention.

In the drawing:

Fig. 1 is a front view of the clasp in the closed position;

Fig. 2 is a side view thereof;

Fig. 3 is a side view with the clasp in the open position;

Fig. 4 is a longitudinal section through the clasp in the open position;

Fig. 5 is a perspective view of the elements separated;

Fig. 6 is a side view of the movable jaw;

Fig. 7 is a plan view thereof; and

Fig. 8 is an end view of this jaw.

This clasp comprises three members, a stationary jaw or body member 10 which also is a rear jaw, a front or movable jaw 11 and an operating lever 12. All three of these parts may be stamped and formed from sheet metal of a suitable gauge. The jaws 10 and 11 are provided with garment clamping means 13 and 14 at their lower or free ends which cooperate to grip the garment between them. These means 13 and 14 may be plain or corrugated or provided with teeth as is found desirable. At the upper end the stationary jaw or body member is provided with a loop 15 having a slot 16 through which may be threaded the supporting web, such as the suspender web, and this loop is connected with the body of the member 10 by a connecting wall 17 which is preferably offset and extends forwardly from the body of the member 10. This wall is provided with a slot or opening 18 for a purpose presently to be described. On the opposite side edges of the member 10 are forwardly extending ears 19 pierced at 20 to form a pivotal mounting for the

operating lever 12, this lever being provided with pintle lugs 21 on the opposite sides of a rearwardly extending flange 22, these lugs seating in the openings 20 to provide the pivotal support for the lever. The body of the lever may be somewhat transversely curved or dished from the rear side to provide ribs or side flanges 23 to add strength and stiffness to the lever and also improve its appearance.

10 The movable jaw 11 is provided at its upper end with a tongue 24, and below this tongue with opposite laterally projecting hinge lugs 25. The rear jaw 10 is provided adjacent its opposite edges with forwardly extending pivot lugs 26 located below the offset wall 17 and between this wall and the pivot ears 19, preferably immediately above the ears 19. The outer ends of these pivot lugs 26 are preferably somewhat rounded and their inner edges are inclined downwardly and inwardly, as indicated at 27, to form a clearance space between the lugs and the ears 19. When the movable jaw is mounted in position, the tongue 24 is seated in the opening 18 in the wall 17 and the hinge lugs 25 are seated on the pivot lugs 26. 15 The hinge lugs 25 are preferably transversely curved or concavo-convex to provide curved depressions or recesses to seat on and receive the free ends of the pivot lugs 26. The tongue 24 and these lugs 25 and 26 form the means for securing 20 the two jaws together.

The jaw 11 is also made of resilient material and the opening 18, tongue 24 and lugs 25 and 26 are so arranged relatively to each other that they normally support the jaw 11 in the open position 25 of Figs. 3 and 4. Therefore, when this jaw is forced toward the stationary or rear jaw 10 the resilient metal is placed under stress and it tends to shift the jaw 11 forwardly to the open position. The flange 22 of the lever 12 engages the front 30 of the jaw 11 and is so arranged that when the lever is swung downwardly to the position of Figs. 1 and 2 this flange 22 by a camming action on the jaw forces it rearwardly to the position of Figs. 1 and 2 and clamps the garment between 35 the jaws. The flange 22 is so arranged with respect to the pivot elements 21 and the body of the lever 12 that its free edge is below the pivot, as shown in Figs. 3 and 4, when the lever is raised and the clasp is open, and will be held in 40 this position by the resilient action of the movable jaw. When the lever 12 is swung downwardly to close the clasp, the free edge of the flange 22 moves past the horizontal plane of the axis of the pivot 21 to a position above this pivot, as 45 shown in Fig. 2, and therefore the resilient action 50 55

of the movable jaw retains the lever in the closed position.

As the hinge lugs 25 of the movable jaw are located immediately above the ears 19 these ears will help to retain the movable jaw in proper position with the tongue 24 in the opening 18 and the hinge lugs 25 properly seated on the pivot lugs 26. The space provided by the inclined walls 27 provides clearance for the lower curved portion of the hinge lugs 25 and permits these lugs to roll on the free ends of the pivot lugs 26. The transverse curvature of the lugs 25 gives them added strength and rigidity, and this curvature may be carried across the body of the jaw for this purpose. Also the tongue 24 may be transversely curved in a similar manner to give it added strength and rigidity. Still further, the jaw may be offset as indicated at 28, and provided with flanges 29 at its opposite side edges to add still further strength and stiffness to the jaw and to improve its appearance.

It will be seen from the above that the clasp is of very simple construction and comprises a minimum number of parts. An important novel feature is the pivot lugs 26 and their novel shape and arrangement cooperating with the rounded hinge lugs 25 on the movable jaw to cooperate with the tongue to secure the jaws together and effectively retain them in proper relative position, and also to permit proper free movement of the movable jaw.

Having thus set forth the nature of my invention what I claim is:

1. A clasp comprising a body member forming a rear jaw and including forwardly projecting ears at its side edges, an integral web loop at the upper end connected with the jaw portion by an offset wall provided with an opening therein, and forwardly projecting pivot lugs at the opposite edges of the member between the ears and said wall integral with the body; a resilient front jaw member forwardly of the first member provided with a tongue extending into said opening and provided with laterally projecting hinge lugs seated on said pivot lugs, said tongue and lugs being so arranged as to form a resilient support for the front jaw tending to shift it forwardly away from the rear jaw, and an operating lever forwardly of the front jaw pivotally mounted in said ears and provided with a rearwardly extending flange engaging on top of the front jaw member below the supports therefor adapted on swinging of the lever toward this jaw to shift it toward the rear jaw to clamp a garment between the jaws and to stress the forward jaw so that it tends to move forwardly.

2. A clasp comprising a stationary jaw and a movable jaw connected adjacent their upper ends and provided with means at their lower ends to clamp a garment, said stationary jaw having a forwardly projecting wall at its upper end provided with an opening, ears extending forwardly from said stationary jaw and integral therewith, forwardly projecting pivot lugs between the ears and said wall integral with said stationary jaw, said movable jaw being provided with a tongue at its upper end seated in said opening and hinge lugs seated on said pivot lugs, said tongue and lugs forming the means for connecting the jaws, the movable jaw being of resilient material and the tongue and lugs being so arranged as to place it under stress when in the closed position so that it tends to move away from the stationary jaw,

and an operating lever pivoted to said ears and provided with a flange engaging the movable jaw to force it toward the stationary jaw to clamp a garment between them.

3. A clasp comprising a stationary jaw and a movable jaw connected adjacent their upper ends and provided with means at their lower ends to clamp a garment, said stationary jaw having an opening adjacent its upper end and provided with integral forwardly projecting pivot lugs below said opening, said movable jaw being seated on said pivot lugs and provided with a tongue at its upper end seated in said opening, said tongue and lugs forming the means for connecting the jaws and the movable jaw being resilient and the tongue and lugs being so arranged as to place it under stress when in the closed position so that it tends to move away from the stationary jaw, and an operating lever forwardly of said jaws and pivoted to the stationary jaw and provided with a flange engaging the movable jaw to force it toward the stationary jaw as the free end of the lever is swung toward the jaws, the free edge of the flange being arranged to move past the pivot for the lever in this action so that the resiliency of the movable jaw retains the lever in the closed position.

4. A clasp comprising a stationary jaw and a movable jaw connected adjacent their upper ends and provided with means at their lower ends to clamp a garment, said stationary jaw having an opening adjacent its upper end and integral forwardly projecting pivot lugs below said opening, said movable jaw being of resilient material and provided with a tongue at its upper end seated in said opening and also provided with transversely curved hinge lugs seated at their concave sides on said pivot lugs, said tongue and lugs forming the means for securing the jaws together and being so arranged as to place the movable jaw under stress when in the closed position so that the resiliency of the jaw tends to shift it away from the stationary jaw, and an operating lever pivoted at its upper end to the stationary jaw and provided with a rearwardly extending flange engaging the front of the movable jaw to force it toward the stationary jaw to clamp a garment between them.

5. A clasp comprising a stationary jaw and a movable jaw connected adjacent their upper ends and provided with means at their lower ends to clamp a garment, a web loop at the upper end of the stationary jaw, said latter jaw being provided with a forwardly projecting wall below said loop provided with an opening, forwardly projecting pivot lugs on and integral with said stationary jaw below said wall, said movable jaw being of resilient material and provided with a tongue seated in said opening and also provided with laterally extending transversely curved hinge lugs seated at their concave sides on said pivot lugs, said tongue and lugs forming the means for connecting the jaws and so arranged as to place the movable jaw under stress when in the closed position so that the resiliency of the movable jaw tends to shift it away from the stationary jaw, forwardly projecting ears on said stationary jaw below and adjacent said pivot lugs, and a lever pivoted in said ears and provided with a rearwardly extending flange engaging the movable jaw to shift it toward the stationary jaw to clamp a garment between them.
